Olle E. Haggstrom and Carl G. Bach, Jr., Jefferson
County, Ky., assignors to General Electric Company,
a corporation of New York

Application September 28, 1959, Serial No. 57,709

Term of patent 14 years

(Cl. D49—1)

FIG. 1

Figure 1 is a front perspective view of a clothes dryer or similar article embodying our new design;

Figure 2 is an enlarged front perspective view of the control panel element thereof;

Figure 3 is a cross section on the line 3—3 of Figure 2 in the direction of the arrows;

Figure 4 is a cross section on the line 4—4 of Figure 2 in the direction of the arrows; and

Figure 5 is a cross section on the line 5—5 of Figure 2 in the direction of the arrows.

The control panel element is stippled in Figures 1 and 2 to indicate color contrast.

The dominant feature of the design resides in the portions shown in full lines. The bottom and side of

the control panel element (not shown) are the same in appearance as the top and sides shown and the back thereof is plain.

We claim:

The ornamental design for a clothes dryer or similar article, substantially as shown and described.
